RICHARD A. FRIEDLANDER AND GEORGE E. GRAVENSTINE, OF DAYTON, OHIO, AS
SIGNORS TO THE S. H. THOMSON MANUFACTURING COMPANY, OF DAYTON, OHIO,
A CORPORATION OF OHIO.

RADIATOR CAP.

Application filed February 21, 1925. Serial No. 10,955.

To all whom it may concern:

Be it known that we, RICHARD A. FRIEDLANDER and GEORGE E. GRAVENSTINE, citizens of the United States, residing in the 5 city of Dayton, county of Montgomery, and State of Ohio, have invented certain new and useful Improvements in Radiator Caps, of which the following is a specification.

This invention relates to new and useful 10 improvements in radiator caps, and particularly those of the locking type.

It is the principal object of our invention to provide a simple and attractive radiator cap which may be economically manufactured 15 for efficient service.

It is a further object of our invention to provide extremely simple means such as a screw, for locking the radiator cap against its unauthorized removal from the neck of 20 the radiator after it has been set in the desired position thereon.

A further object of the invention is to provide for the cap a simple hinged cover to which a temperature indicating instrument 25 may be secured against removal therefrom by an unauthorized person.

It is still a further object of our invention to provide means for limiting the opening movement of the hinged cover beyond a 30 point where the glass temperature indicating instrument carried by it will strike the radiator and be broken by the impact.

A further object of the invention is to provide between the cover and the cap a 35 hinged connection comprising two hinge pins that cannot be driven out by an unauthorized person.

It is still another object of the invention to provide a convenient catch or clip member 40 for locking the cover to the cap on the side opposite the hinged connection between them.

Further important and incidental objects 45 will be brought out in the following specification and particularly set forth in the subjoined claims.

In the accompanying drawings, Figure 1 is a front view of our improved radiator cap. Figure 2 is a longitudinal sectional view taken on the line 2—2 of Figure 1, showing the general construction of the cap. Figure 3 is a sectional view taken on the 50 line 3—3 of Figure 2, showing the screw means for locking the cap to the neck of

the radiator against its removal by an unauthorized person. Figure 4 is a rear elevational view of the radiator cap, showing the dual hinge pin connection between the cover and the cap. And Figure 5 is a side elevational view of the rear portion 60 of the cap, showing the hinge stop means for limiting the outward movement of the cover.

Referring to the accompanying drawings for a detailed description of the form of embodiment of our invention illustrated therein, the numeral 1 designates the bottom part of a radiator cap having an externally threaded skirt 2 adapted to be screwed into an internally-threaded radiator neck 3. (See Figures 1 and 2.)

Formed on the back side of the bottom part 1 of the cap, and extending above its top surface, is a wide U shaped hinge-pin receiving projection 4. Loosely fitted between the arms 5, 5 of this projection is the lower part of a T shaped tongue or flange 6 formed on the back side of a cover plate 7 formed with two oppositely-disposed radial arms 8, 8. Formed in each 80 side of the tongue 6 a short distance below its flanged top is a horizontal hole 9 to receive a short hinge-pin 10 that is tightly secured in a registering hole in a respective arm 5 of the U shaped projection 4 on 85 the bottom part 1 of the cap. These hinge-pins 10, 10, which are difficult of removal by an unauthorized person, hingedly support the cover plate 7 at the back side of the cap. (See Figures 4 and 5.)

Formed in the middle portion of the cover plate 7 is a hole to receive the externally threaded stem 11 of a temperature indicating instrument 12 of a common type. Surrounding the upper portion of the stem 95 11 of said instrument is a split lock washer 13 which is forced against the cover plate by a suitable nut 14. (See Figure 2.) Formed in this nut is a threaded tap hole to receive a screw 15 which, after being forced 100 into tight engagement with the threaded stem 11 of the temperature indicating instrument 12, may be cut off approximately flush with the nut to prevent its removal so that the temperature indicating instrument may 105 be locked on the cover plate.

When the cover plate 7 is opened, the flange top ends 16, 16 of the tongue 6 on

it will engage the arms 5, 5 on the U shaped projection 4 of the bottom part of the cap to stop the swinging movement of the cover plate before the temperature indicating instrument 12 which it carries can knock or strike the radiator (not shown) and be injured by the impact. (See Figure 5.)

Formed within the top part of the bottom portion 1 of the radiator cap is an internal, 10 annular flange 17 which acts as a support for a gasket 18 that an internal bottom flange 19 on the cover plate 7 is adapted to engage when the cap is closed thereby, thus sealing the opening in the cap against the 15 escape of liquid from the radiator.

For the purpose of locking the cover plate 7 tightly in its closed position against the bottom part 1 of the cap, the following means are preferably employed. Projecting 20 from the front side of the cover plate 7 are two lugs 19, 19 formed with oppositely-disposed holes which receive a pivot pin 20 that passes through a transverse hole in an inwardly projecting ear 21 formed on 25 the top part of a catch member 22 and positioned between said lugs. At the lower end of the catch member 22 there is formed an inwardly projecting lug 23 which is adapted to engage under a ledge 24 on the bottom 30 part of the cap, to draw the cover plate 7 tightly against the gasket 18. The catch member 22 is preferably enlarged at its lower end, merging into a curved tip 25 which may be easily grasped by the fingers to engage 35 the lug 23 with, and disengage it from, the ledge 24 on the bottom part 1 of the cap. (See Figures 1 and 2.)

For the purpose of locking the cap on the radiator neck 3 against its removal by an 40 unauthorized person, the following means are provided. Formed on the inner surface of the bottom part 1 of the cap, preferably below the ledge 24, is a vertical boss 26 formed with an axial hole which extends from its 45 bottom upwardly and through the flange 17 upon which the gasket 18 rests. (See Figures 2 and 3.) The externally threaded wall of the bottom part 1 of the cap is formed with a vertical slot that is opposite the axial hole in the boss 26 to permit the projection therethrough of the threads on a screw 27. The axial hole in the boss 26 is adapted to vertically receive this screw 27 whose 50 threads run oppositely to the threads on the inner surface of the radiator neck and which are adapted to engage said threads on the latter through the slot in the 55 bottom part 1 of the cap. Since in this in-

stance the radiator neck is formed with a right hand thread, a left hand screw 27 is employed, so that after the cap has been screwed down tightly into the neck of the radiator, with its arms 8, 8 in proper alignment with the front of the latter, the screw 27 may be inserted in the boss 26 to project 60 its threads, through the slot in the cap, into locking engagement with the oppositely running threads in the radiator neck to prevent the removal of the cap from it by an unauthorized person. Even after the screw 65 is taken out, the radiator neck threads will have been so blunted by it as to make it extremely difficult to take the cap off.

The screw 27 thus provides an extremely simple and out of the way means for locking the cap on the radiator neck of an automobile.

Having described our invention, we claim:

1. The combination with a threaded radiator neck, of a threaded radiator cap 80 adapted to be screwed thereon, and a locking member bearing an external thread running oppositely to the thread of the radiator neck for vertical insertion between the latter and the radiator cap, for the purpose specified.

2. The combination with a threaded radiator neck, of a threaded radiator cap adapted to be screwed thereon and formed 90 with a vertical hole which opens through one side of the cap, and a screw insertible in said vertical hole, said screw having a thread running oppositely to the thread of the radiator neck and adapted to lockingly engage the latter thread through the vertical hole in the side of the radiator cap if the latter is turned, for the purpose specified.

3. The combination with a radiator neck formed with an internal thread, of a radiator cap having an external thread adapted 100 to be screwed in said radiator neck, said cap formed with a vertical hole which opens through the externally threaded portion of one side of the cap, and a screw insertible in said vertical hole, said screw having a thread running oppositely to the thread of the radiator neck and adapted to lockingly engage the latter thread through the vertical hole in the side of the radiator cap if the latter is turned, for the purpose specified.

In testimony whereof we have hereunto set our hands this 20th day of February, 1925.

RICHARD A. FRIEDLANDER.
GEORGE E. GRAVENSTINE,
